UNITED STATES PATENT OFFICE.

WILLIAM S. ELLIOTT, OF PITTSBURGH, PENNSYLVANIA.

STRAINER SYSTEM.

1,070,788.

Specification of Letters Patent. Patented Aug. 19, 1913.

Application filed June 27, 1910. Serial No. 569,083.

To all whom it may concern:

Be it known that I, WILLIAM S. ELLIOTT, a resident of Pittsburgh, Allegheny county, and State of Pennsylvania, have invented a new and useful Strainer System, of which the following is a full, clear, and exact description, reference being had to the accompanying drawings, forming part of this specification.

10 My invention relates to strainer apparatus and more particularly to the strainers for intake pipes submerged in lakes or other bodies of water.

15 The object of the invention is to provide a strainer apparatus of this character of simple and inexpensive construction, and in which the strainer proper may be easily raised and lowered for cleaning, repairs, etc.

20 The invention also provides for closing off the pipe by a valve, when the strainer is removed.

25 The invention resides particularly in the operating system for the strainer and valve, whereby the inlet may be closed while the strainer is raised for cleaning.

30 In the accompanying drawings Figure 1 is a side elevation of strainer apparatus embodying my invention. Fig. 2 is a front elevation of the same. Fig. 3 is a horizontal 35 sectional view on the line III—III of Fig. 2. Fig. 4 is a detail view of the modified form. Fig. 5 is a sectional plan view showing another modification.

In the drawing, 2 represents the elbow 35 portion of an intake pipe 3, this elbow terminating in a double guide portion 4, one part of which guide receives the valve 5, having a rotatable stem 6 extending to above the surface, with its upper portion screw 40 threaded and provided with a hand wheel 7. The screw threaded portion extends through a suitable nut 6^a in the support 8 so by turning the hand wheel 7 the valve may be shut off from the inlet flow to the 45 intake pipe or may be raised to allow the flow.

To the sides of the valve casing are secured horizontal brackets 9—9, the outer ends of which receive vertical guide rods 10 50 extending up above the surface and secured to the support 8 or any other part of the supporting frame work. The strainer 11 preferably consists of a perforated basket having U-shaped side guides 11^a secured to 55 it which slide over the guide rods 10 and

having inner end guides 11^b filling the recesses outside the valve guide recesses in the intake elbow, as shown in Fig. 3. The basket is provided with a chain 12 from which a chain 13 leads upwardly to and over a chain 60 sheave 14 on a winding shaft 15. The other end of the chain is preferably provided with a counterweight 16, and the shaft may be provided with a suitable operating handle 17, and a ratchet wheel 18 engaged by a 65 hand controlled pawl 19. The shaft 15 is mounted in bearings on the supports 8 which form part of a framework. This framework may be of any suitable character, and sets into the water with its upper portion 70 projecting above the surface.

In the use of the device, the valve is lifted within its guides to open the intake elbow and the basket rests in its lowermost position, thus straining the water entering the 75 pipe. When it is desired to lift the basket for repairs, cleaning etc., the shaft is actuated to move the valve downwardly within its guides until the entrance of the pipe is shut off. The shaft is then actuated to wind 80 up the lifting chain and thus raise the basket along its guides until it is above water, where it can be repaired, cleaned, etc. The basket may then be lowered on its guides to its original position and the valve then lift- 85 ed, when the parts are again ready for operation.

Instead of a single intake pipe a crib may be provided with a series of downwardly projecting inlet pipes, as shown in plan view 90 of Fig. 4, and in this case each of these pipes would be provided with my valve and strainer system as shown in the first figures, the valve and strainer system being preferably independently operable for each inlet 95 pipe to the crib. In this figure 20 are the inlet pipes to the crib 21 from which the outflow pipe 22 leads.

The mouth of the inlet pipe may project in any desired direction and a single pipe 100 may be provided with a pair or more of the strainer and valve connections, as shown in Fig. 5, in which 23 is the inlet pipe and 24 the strainers, each mounted as in Figs. 1, 2 and 3, and separably operable so that 105 either branch of the inlet may be closed and its strainer raised to the surface.

The advantages of my invention result from the simplicity and ease of the operation of the device. The valve guides extend 110

only a sufficient distance above the pipe to insure proper guiding in lifting to open the inflowing end; while the basket guides extend above the surface of the water. The basket is easily and quickly raised and lowered and is accurately guided to its proper position when lowered.

Many changes may be made in the form and arrangement of the intake pipe, the 10 number of inflowing nozzles, etc., without departing from my invention.

I claim:

1. In strainer apparatus for water systems, a submerged intake nozzle, a submerged valve for opening and closing said nozzle, a strainer element, and separate actuating means extending downwardly into the water for the valve and strainer element whereby the valve may be opened or closed and the strainer element may be lowered from the surface into operative relation to the said nozzle and again raised to the surface at will; substantially as described.
2. In strainer apparatus for water systems, a submerged intake nozzle, a submerged valve for controlling said nozzle, a strainer element for said nozzle, and actuating means for said valve and element and 30 extending upwardly therefrom above the surface of the water, together with guides

for the said valve and element; substantially as described.

3. In strainer apparatus for water systems, a submerged intake nozzle having a 35 valve seat and a strainer seat, a valve member, a strainer element, and actuating means for said member and element extending upwardly above the surface of the water, together with upwardly extending fixed 40 guides for said member and element; substantially as described.

4. In strainer apparatus for water systems, a submerged intake nozzle, a submerged valve for opening and closing the 45 nozzle, a strainer element for the nozzle, a supporting structure above the water, valve actuating means carried on said structure and extending downwardly into the water to said valve, guiding means for the strainer element extending downwardly from said structure, and actuating means whereby the said element may be raised and lowered on the guiding means; substantially as described.

In testimony whereof, I have hereunto set my hand.

WILLIAM S. ELLIOTT.
